UNITED STATES PATENT OFFICE

JUSTIN ANDRÉ HECTOR FEDI, OF PARIS, FRANCE

MACHINE FOR MECHANICALLY FINISHING ROADWAY CONCRETE COVERINGS

Application filed August 19, 1930, Serial No. 476,400, and in France August 29, 1929.

This invention relates to machines for mechanically finishing roadway concrete coverings.

5 *1. Generalities concerning concrete coverings*

Concrete coverings for roadways are usually executed with fine stone elements.

Now, the use of large adequate stone elements:

10 (1°) allows to obtain much more considerable resistance to wear and breaking, which is very important particularly for the covering of roadways where the traffic is heavy and intense.

15 (2°) allows to obtain rougher coverings, the roughness or rugosity of which is naturally maintained in proportion to the wear of the coverings, as it results from the very constitution of the latter throughout its thickness. This quality is obviously very important, particularly for the covering of roadways where the traffic is rapid.

20 But the production of a perfectly smooth rolling surface, which is so easy to obtain with coverings presenting a cement layer or a rolling layer made of concrete composed of fine stone elements, is difficult and necessitates special handling and arrangements when a rolling layer composed of large elements is to be produced.

25 However, the perfection of the finish of the rolling surface so appreciated by users of the road, does not certainly present any interest if it is but momentary, owing to the rapid deterioration of a covering, the resistance of which is insufficient for the traffic it has to support, or if it is obtained to the detriment of the proper adherence of the wheels of vehicles on the covering, the use of which is then very dangerous.

30 It is therefore necessary to carry out the perfection of the finish only according to conditions allowing to obtain, in their integrality, the primordial qualities of resistance and permanent rugosity or roughness of concrete coverings.

35 The present invention has particularly for object to allow of mechanically executing concrete roadway coverings with a rolling layer composed of large stone elements, pos-

sessing all the special qualities of this type of concrete covering, and presenting moreover the perfection of the finish of the rolling surface which is particular to concrete coverings composed of fine elements.

40 It is to be understood that the said invention is, a fortiori, applicable for mechanically executing concrete coverings composed of fine elements, this construction being much more easy than the preceding one.

2. *Better fundamental method of execution*

The construction of a concrete roadway covering necessitates, among others, two operations; ramming and finishing of the covering.

45 These two operations are usually effected with the same mechanical apparatus or the same machine:

—either 1°—the usual street-roller for ballasting, but of a light type;

—or 2°—pneumatic, mechanical or electric rammers;

—or 3°—a curved beam which, guided along the longitudinal forms or moulds, mechanically rams, by reproducing in a single operation, the entire transverse profile of the covering strip executed (transverse gauge finishing apparatus);

—or 4°—a straight beam, one or two meters long, mounted in a frame carried by two operators, and which vibrates, in the vertical direction, rapidly, but with a very small stroke, under the action of pneumatic vibrators (vibrating rammer).

50 Now, the most efficient ramming apparatus must exert, on fresh concrete, very high unitary pressures, which can then be simultaneously exerted on a small surface only,

whilst the finishing machines, which execute this operation in the most perfect manner, usually exert, on fresh concrete, but relatively small unitary pressures, but these pressures must be exerted at the same moment on a width or length of covering as large as possible.

55 It results from this fundamental observation that for effecting these two operations without totally or partially executing one

55

60

65

70

75

80

85

90

95

100

of these operations to the detriment of the other, that is to say:

- 5 (1°) for effecting a very powerful ramming of the concrete, this ramming, in the same measure as the other features of the covering, always largely improved the resistance of the same and is, in any way, indispensable for concrete coverings composed of large stone elements; and,
- 10 (2°) for obtaining a perfect finishing of the covering, this finishing, in the same measure as the other features, renders it much more agreeable for the traffic, reduces to the minimum the consumption of fuel, allows the highest speeds, and also contributes to the good preservation of the covering. I suggest the execution of each of these ramming and finishing operations with entirely distinct machines or apparatus, so as to avoid any interference, even partial, between these two operations which are so essential.

3. Better ramming method

25 For effecting ramming, I suggest the use of rammers.

In fact, these apparatus, whilst being easily displaceable by the operator utilizing them, are capable of delivering, on fresh concrete, and at a sufficient speed, blows which only striking on a surface of one or two square decimeters, are very powerful per unit of surface, so that the stone elements, even of relatively large size of rammed concrete, are successfully and very powerfully pressed against each other.

It is to be further mentioned, for overcoming a common objection, that the regularity of ramming, by means of rammers, of a covering surface, can be obtained in practice in quite a satisfactory manner by allotting to each rammer, and for each transverse strip of covering, a portion of surface to be rammed, each rammer being displaced on this surface at a suitable average rate and so as to entirely cover it at least twice, and particularly one time by tracing longitudinal bands and the other time by tracing transverse bands, crossing the first ones at a right angle.

4. Improved finishing method

In order to define the best finishing method, I recall to mind that geometrical perfection of the profiles across a roadway covering is practically indispensable, only relatively, and particularly in the proportion where, owing to the absence of holes and considering a light gradient, it ensures, in the transverse direction, the regular flow of rain water to the gutters or side ditches, the latter being adapted to receive this water and to cause it to flow in a longitudinal direction.

On the contrary, the geometrical perfection of the lengthwise profiles is, even in

practice, desirable in a nearly absolute manner, as it is usually by following these profiles that vehicles pass over roadway coverings. Now, it is necessary that the longitudinal profiles should nearly exactly coincide with the theoretical profiles in order that this passage may take place:

- (1°) for all vehicles with the minimum of resistance to rolling.
- 75 (2°) for rapidly moving vehicles by giving rise only to the minimum of shocks and trepidations consistent with the speed obtained and with the more or less perfect construction of the vehicle used.

Now, the verification of the perfection of the finish of an ordinary transverse covering strip or band in straight alignment can be effected;

(a) either by displacing on the straight forms or moulds, laterally secured according to the lengthwise profile, a gauge reproducing the crosswise profile;

80 (b) or by moving on forms or moulds reproducing the crosswise profile and secured at both transverse ends of the covering strip or band to be verified, a straight ruler reproducing the lengthwise profile.

85 Theoretically, both methods of verification have obviously the same value, but in practice, it is the method (b) which, because it provides direct verification of the lengthwise profile, allows an operator to better control the perfection of these profiles, which perfection has the priority over the perfection of the crosswise profiles.

90 For this reason, to the finishing obtained according to the method (a), either by hand, or by means of finishing machines provided with a movable transverse gauge, I distinctly prefer (all things being equal) the finishing executed according to the method (b).

95 For effecting the finishing according to the method (b), it has already been proposed to use a roller having a relatively small diameter, a length slightly greater than or equal to that of the transverse covering strip and of suitable weight, and to cause it to roll alternatively in one direction and the other on guides (or between guides) shaped according to the crosswise profile to be obtained and secured at each transverse end of the transverse covering strip or band to be finished.

100 This solution, although still manual, is obviously much preferable to that obtained by utilizing, with similar guides, a simple ruler, or better a straight beam of adequate weight, which is alternately lifted at each end and allowed to drop, by slightly displacing it, after each blow, in the transverse direction.

5. New finishing machine

105 The present invention also relates to a new machine for the finishing of concrete roadway coverings, which machine mechanically

executes the finishing operation effected by a roller of great length and small diameter rolling on transverse guides.

This machine, simple, strong, very easily operable, is suitable for concrete coverings of any type, as well for coverings composed of large stone elements, as for those composed of small elements, and for any width and profile of roadways.

It is mainly characterized by two longitudinal rollers of small diameter relatively to their length, the latter being slightly greater than that of the transverse covering band to be finished.

The accompanying drawings illustrate a machine for finishing roadway coverings, devised in accordance with the present invention.

Fig. 1 is a diagrammatic elevation of the machine as seen in the longitudinal direction of the road.

Fig. 2 is a corresponding partial plan view.

Figs. 3 to 9 illustrate a form of construction of the machine, the principle of which is diagrammatically illustrated in Figs. 1 and 2.

Fig. 3 is a plan view of the machine in its entirety.

Fig. 4 is a corresponding side elevation.

Fig. 5 is a vertical section, on an enlarged scale, made according to line I—I of Fig. 3.

Fig. 6 is a vertical section, on an enlarged scale, made according to line II—II of Fig. 3.

Fig. 7 is a section made according to line III—III of Fig. 5.

Fig. 8 is a section, on an enlarged scale, made according to line IV—IV of Fig. 3.

Fig. 9 is a horizontal section made to line V—V of Fig. 5.

As diagrammatically illustrated in Figs. 1 and 2, the apparatus comprises two longitudinal rollers 1 and 2 pivoted at 3 and 4 on a frame 5.

These rollers are both driving rollers and are actuated by the engine diagrammatically illustrated at 6. The driving shaft is shown at 7. This shaft is arranged parallel to the rollers 1 and 2 and it drives, through the medium of a speed reducing device 9, a shaft 10 co-axial with the first one, which transmits the movement to the rollers in the same direction for instance by means of chains 11.

Some of the bearings supporting the axles of the longitudinal rollers are movable, and they are so movable that, even in the course of the finishing operation, exact parallelism of the longitudinal rollers, or a slight momentary deviation of one of them may be easily obtained. This deviation is particularly useful for allowing to easily and progressively modify, during the finishing operation, the general orientation of the machine by a slight oblique displacement of the latter.

The engine also transmits its movement, through the medium of a transverse shaft 12, to a transverse roller 13 (transverse driving

roller). Another transverse roller which serves for steering but not for driving, is arranged at the other end of the machine and is not illustrated in the drawings. Both transverse rollers are so mounted as to be lifted, to a sufficient height, above the ground, when the machine is in working position as illustrated, or, on the contrary, to rest on the ground so as to allow the longitudinal displacement of the entire machine on these rollers 13. For that purpose, the rollers 13 are, for instance, mounted on a support 15 capable of rotating about a shaft 16. Any lifting apparatus, such as a mechanical or hydraulic jack 19, allows of giving to the support 13 the suitable position and of causing the machine to rest either on the longitudinal rollers 1 and 2 during the finishing operation, or on the transverse rollers 13 during the transport from a transverse covering strip to another.

For this transport (longitudinal progression) the movement is transmitted from the shaft 12 to the shaft 16, then from this shaft to the transverse driving roller, for instance by a chain 20.

The weight of the machine is sufficient in order that the finishing action of the rollers be efficient, without however being too high for avoiding the formation, in front of the longitudinal rollers passing on fresh concrete, of concrete pads prejudicial to the regularity of the finish. An excessive weight would also necessitate the use of a very powerful engine, with all the inconveniences this would cause for such a machine.

In accordance with the above mentioned principles, the machine is exclusively a finishing apparatus the essential function of which is to regularize, by application of the best actual method, the surface of the concrete (composed of large elements) forming the rolling layers of concrete coverings, this operation being however effected only immediately after powerful and repeated ramming of the concrete, by rammers or other ramming or compression apparatus.

This machine must therefore act only as a finishing machine, but it fulfills this function in the best conditions.

It is to be noted that the longitudinal rollers 1 and 2 of the machine have a length slightly greater than the transverse covering band or strip to be finished, and that the excess of length must be sufficient for ensuring a suitable connection of the finishing surface of the new transverse band with the preceding transverse band.

The concrete coverings are provided with transverse contraction joints, located at about 10 meters from each other and the interval between two joints is executed in two successive operations of application of concrete, each operation being consequently executed

on a transverse strip or band of about 5 meters, in length.

For executing such transverse bands, the finishing machine provided with longitudinal rollers must therefore have rollers about 5.50m long.

It is obvious that the machine can be provided with rollers of very different length and this according to the length of the trans-¹⁰ verse covering bands executed in a single operation.

Thus, for executing a concrete covering on a road having a large number of turns, it will be useful to employ, for executing curved ¹⁵ portions of the covering, a finishing machine provided with longitudinal rollers having a length of only 2.50 to 3 meters for instance. But it will probably not be desirable to go below this limit.

When the covering in course of execution is not laterally bordered by an old roadway or by a solid driftwork at the same level, the longitudinal progression of the machine on the covering of these two transverse bands ²⁵ or strips seems to be the best method.

But it is necessary that this progression should not deteriorate the regularized surface of the finished transverse band. In order to avoid this inconvenience:

(1°) the transverse rollers have a sufficient length and diameter;

(2°) the above progression takes place on a raceway constituted by a sheet metal plate of sufficient thickness, slightly wider than the transverse rollers and arranged on the length of the finished transverse covering band and, eventually, also on the length of the transverse covering band ready to be finished.

(3°) the progression takes place on the portion of the finished covering, the cross-wise profile of which is most similar to the rectilinear profile of the rollers.

In these conditions, as soon as the finishing of a transverse covering band is terminated and it is desired to cause the machine to pass on the following transverse covering band, the sheet metal plate constituting the raceway is first arranged at the required place, and this operation can be effected owing to the length of the sheet metal plate which exceeds that of the transverse covering band, by operators who stand, with the required precautions, outside the fresh concrete the finishing of which has just been terminated.

The machine is then brought, by transverse progression, on the raceway. Then, the transverse rollers are placed in working position and, finally, the machine is caused to pass, by longitudinal progression, on the transverse covering band which is ready to be finished, after having eventually placed on the latter band and in alignment with the first one, a second sheet metal plate of similar type forming a raceway.

As the length of the transverse rollers must not be too small and as these rollers must be arranged between the longitudinal rollers, without ever being hindered in any of the positions they are caused to assume, it is these conditions, added to those relating to the proper stability of the machine and to the housing of the other parts, which determine the spacing apart of the longitudinal rollers.

This spacing apart is not however exaggerated as, to a certain extent, the smaller it is, the better the machine is adapted to effect the finishing of covering bands of small width.

It is to be noted that the longitudinal rollers, whilst being sufficiently rigid for preserving without material distortion their cylindrical shape, are given a small diameter in order that the rolling should practically continue up to the side ends of the covering.

Finally, for a long transport of the machine by road, from one working place to the other, the frame can be provided, for instance, at one end or at a suitable intermediate point, with a fixed axle on which can be mounted carrying wheels and, at the other end, with a bolster-bolt which can receive a suitable bogie, so as to allow transport, by dragging of the machine, which thus solely rests on the above mentioned detachable wheels. Consequently, the said wheels would be mounted on the said axle after the frame of the machine has been sufficiently lifted in order that all the longitudinal and transverse rollers may remain, during dragging, at a sufficient height above the ground, so as not to hinder the progression.

In the form of construction illustrated in Figs. 3 to 9, the machine comprises a frame constituted by two parallel longitudinal bearers 21 and 22 and cross members bracing these longitudinal bearers. The two end cross members 23 and 24 support bearings 25 and 26, in which are mounted trunnions provided at the ends of the large finishing rollers 1 and 2. Two of these trunnions extend beyond their bearings and rigidly carry pinions 27 and 28 connected, by chains 29 and 30, to two pinions 31 arranged on a plate 32 which, by means of a clutch 33, the arrangement of which may be variable and does not form a part of the invention, is connected to a shaft 34 on which it is loosely mounted. This shaft 34 is journaled in bearings 35 carried by the cross members 36 and 24 of the frame. On the said shaft 34 are rigidly secured a spur wheel 37, a sprocket wheel 38 and a bevel pinion 39.

The spur wheel 37 constantly meshes with a gear wheel 40 which belongs to a sliding gear 41 loosely mounted on a shaft 42 journaled in bearings 43 carried by the cross members 36 and 44. The pinion 38 is connected, by a chain, to a pinion 45 which belongs to a second sliding gear 46 also loosely

mounted on the shaft 42. Each of the sliding gears 41 and 46 is provided with a clutch cone 47 arranged adjacent to one of the elements of a double cone 48 and prevented from 5 rotating and moving on the shaft 42. Two levers 49 and 50 are loosely mounted on the shaft 42 and are provided with inclines 51 in contact with fixed inclines; these levers are connected in translation, but not in rotation, 10 with the sliding gears 41 and 46, so that the latter are subjected to translation along the shaft 42 when the levers 49 and 50 are angularly moved. The angular displacements of the levers 49 and 50 derive from those of 15 shafts 51^a and 52 provided, at one end, with levers 53 and 54 connected, by links 55 and 56, to the levers 49 and 50. The control of the shafts 51^a and 52 takes place by means of operating bars 57 and 58 arranged within 20 reach of the driver of the machine seated on a seat 59. The shaft 42 carries a pinion 60, connected, by a chain, to a pinion 61 mounted on a counter-shaft 62 journalled in bearings 63 supported by cross members 65 and 66 of the frame and which, through the 25 pinions 67 and 68 and the chain 69, is connected to the shaft of a heat engine 6 supported by cross members 70.

The rollers allowing the machine to move 30 longitudinally are, in the form of construction under consideration, three in number: a driving roller 13 and two steering rollers 71. The driving roller 13 is journalled in two bearings secured at the ends of racks 72 vertically guided relatively to the longitudinal bearers 21 and 22 and constantly gearing with pinions 73, rigidly mounted on a shaft 74, journalled in bearings 75 supported by the longitudinal bearers of the machine frame. 35 At one of its ends, the shaft 74 carries a worm wheel 76 constantly gearing with a worm 77, rigidly mounted on a shaft 78, journalled in bearings 79, carried by the cross members of the machine frame, and connected, by pinions 40 80 and 81 and a chain 82, to a shaft 83 provided with a hand crank 84, one of the journals of the roller 13 is connected, by pinions 85 and 86 and a chain 87 to a clutch 88 loosely mounted on a shaft 89 on which is 45 secured a bevel pinion 90 gearing with the bevel pinion 39 of the shaft 34. A second clutch 91, mounted on the shaft 89, but longitudinally movable on the latter can, by means of a lever 92 within reach of the driver seated 50 on the seat 59, be thrown in gear with the clutch 88 or released from the latter. The steering rollers 71 are loosely mounted on a shaft 93 supported, at its middle portion, in a fork piece 94 (Figs. 5 and 9) provided 55 at the end of a rack 95 vertically guided relatively to the machine frame. The shaft 93 is pivoted on an axis 96 of the fork piece 94, so that it can be subjected to changes of orientation in a plane parallel to the machine frame. These changes of orientation 60

derive from the angular displacements of a shaft 97 supported by a bearing secured on the cross member 98 and provided, on the one hand, with an operating hand wheel 99 within reach of the driver of the machine and, 70 on the other hand, with a pulley 100 on which is secured a cable 101 each of the sides of which, after passage over transmission pulleys 102, is attached to an end of the shaft 93.

The rack 95 constantly gears with a pinion 103, rigidly mounted on a shaft 104, connected to the shaft 78 by the worm wheel 105 and the worm 106.

The operation of the machine is as follows:

During operation, when the finishing rollers 1 and 2 must roll on the concrete covering of a roadway, the rollers 13 and 71 have been simultaneously lifted relatively to the frame, by means of the crank 84 operated in the suitable direction, in order to lift the racks 72 and 95 by means of the pinions 73 and 103 connected to the shaft 78. The driver, by acting on a lever 107 engages the plate 32 and the shaft 34 and ascertains if the lever 92 is in such a position that the clutches 91 and 98 are not in engagement; by then acting on one or the other of the bars 57 and 58, he engages one or the other of the cones 47 with the double cone 48 rigidly mounted on the shaft 42. The engine 6 then drives both rollers 1 and 2 95 in the same direction and the entire machine moves on the surface of the concrete from left to right or from right to left, according as the driver has acted on one or the other of the bars 57 and 58. For ensuring the propulsion of the machine in the longitudinal direction, the crank 84 is operated so as to raise the frame relatively to the rollers 13 and 71 which bear on the ground. By acting on the lever 92 and on one or the other of the bars 57 and 58, the driver causes the machine to move 100 forward or backward and steers it by means of the hand wheel 99.

It will be moreover noted that, in accordance with the invention, the longitudinal rollers 1 and 2 are mounted, at their ends, in spherical member bearings; means are also provided for displacing these bearings in order to regulate the parallelism of these rollers or for causing the latter to form a predetermined angle. The bearings of the shaft 42 are, preferably, also mounted on spherical members.

What I claim as my invention and desire to secure by Letters Patent is:

1. A machine for finishing concrete roadway coverings comprising a frame, two longitudinal rollers journalled in the frame, an engine on the frame, means for temporarily displacing the two longitudinal rollers while rotating in either direction from the engine for driving, the machine resting on the said longitudinal rollers which progress transversely relative to the road, two transverse rollers mounted on the said frame, one of these 125

rollers being a steering roller and the other driven temporarily in rotation from the said engine, means for raising or lowering one of the said rollers for allowing the machine to rest either on the longitudinal rollers or on the transverse rollers, as and for the purpose set forth.

2. A machine for finishing concrete roadway coverings comprising a frame, bearings on the frame, two longitudinal rollers journaled in the bearings, an engine on the frame, means for displacing in a horizontal plane one of the said bearings, the bearing which corresponds to the said bearing moving in translation being a bearing with ball and socket joint, means for temporarily displacing the said longitudinal rollers while rotating in either direction from the said engine for driving, the machine resting on the said longitudinal rollers which progress transversely relative to the road, two transverse rollers mounted on the said frame, one of the transverse rollers being driven temporarily in rotation from the engine, the other transverse roller being oriented from the steering wheel of the machine, means for raising and lowering the rollers for allowing the machine to rest either on the longitudinal rollers or on the transverse rollers, as and for the purpose set forth.

3. A machine for finishing concrete roadway coverings comprising a frame, bearings on the frame, two longitudinal rollers journaled in the bearings, an engine on the frame, means for displacing in a horizontal plane one of the said bearings, the bearing which corresponds to the said bearing moving in translation being a bearing with ball and socket joint, means for temporarily displacing the said longitudinal rollers while rotating in either direction from the said engine for driving, the machine resting on the said longitudinal rollers which progress transversely relative to the road, two transverse rollers mounted at the ends of supports moving angularly, lifting jacks for angularly displacing the said supports for allowing the machine to rest either on the longitudinal rollers or on the transverse rollers, as and for the purpose set forth.

4. A machine for finishing concrete roadway coverings comprising a frame, bearings on the frame, two longitudinal rollers journaled in the bearings, an engine on the frame, means for displacing in a horizontal plane one of the said bearings, the bearing which corresponds to the said bearing moving in translation being a bearing with ball and socket joint, means for temporarily displacing the said longitudinal rollers while rotating in either direction from the said engine for driving, the machine resting on the said longitudinal rollers which progress transversely relative to the road, two transverse rollers, one of these transverse rollers,

which is a steering roller, being constituted by two secondary rollers coaxially journaled about a horizontal axle or shaft which is mounted for rotating on a vertical rack moving in translation, the other transverse roller which is temporarily driven in rotation from the engine being mounted on vertical racks also moving vertically in translation, means for temporarily displacing the said racks in translation in either direction for allowing the machine to rest either on the longitudinal rollers or on the transverse rollers as and for the purpose set forth.

In testimony whereof I have signed this specification
